UNITED STATES PATENT OFFICE.

WILLIAM O. FROME, OF WATAGA, ILLINOIS.

TUBE EXPANDER AND FLANGER.

1,088,336.

Specification of Letters Patent. Patented Feb. 24, 1914.

Application filed February 17, 1913. Serial No. 748,851.

To all whom it may concern:

Be it known that I, WILLIAM O. FROME, a citizen of the United States, residing at Wataga, in the county of Knox and State of Illinois, have invented a new and useful 5 Tube Expander and Flanger, of which the following is a specification.

My invention relates to devices for expanding that portion of boiler flues which lie beyond or inward of the flue-sheet, and 10 for flanging or swaging the end portions of the flues which lie exterior thereto.

To some little extent boiler tubes or flues expand or contract as they are heated or 15 cooled. The expansion is both longitudinal and transverse of the flue. With these basic facts in view the primary object of the invention is to provide an expander which will enlarge that portion of the flue which lies 20 just beyond the flue-sheet in such manner that it forms a taper or wedge, which when the flue is heated will in expanding longitudinally force itself (after the fashion of a wedge) into the aperture provided in said sheet; and as it is crowding itself longitudinally therewith, the transverse expansion 25 will force it even more tightly into the aperture.

Minor objects will be in part definitely 30 pointed out and in part obvious.

In the accompanying drawing, which illustrates a preferred embodiment of the invention:—Figure 1 is a longitudinal, central sectional view; Fig. 2, a similar view, 35 the rollers reversed from the positions shown in Fig. 1, and some of the parts not shown; Fig. 3, a plan, seen from the front end of the device, the parts in the same relative positions as in Fig. 1; and Fig. 4, 40 an elevation, a fragmental detail. Fig. 1 illustrates the position of the rollers for expanding the inner portions of the flues; Fig. 2, the positions which they occupy in flaring 45 the flue ends.

I have sought to provide a casing and 45 rollers having novel relationship—the slots and rollers being of such relative sizes and outlines that a portion of the latter may project bodily therethrough, but another 50 portion, being of slightly greater cross-section or diameter the width of the slots, will project only slightly therethrough. In these slots the rollers may be reversed or turned end-for-end in order that the two 55 operations, heretofore requiring either a compound tool or two tools, may be per-

formed in an efficient manner and with despatch.

Referring to the parts by numerals, the same one of which is uniformly employed 60 to indicate the same part, 2 designates a casing having an annular flange 3 and an axial bore 5. Its wall is provided with oblong rectangular slots 4.

6 designates a loose collar having bosses 7. 65 9 is a restraining ring, preferably of wire. These parts are old in the art and to them specifically I make no claim.

10 is a tapered mandrel having a ratchet-faced head 11 and a constricted tip 12, the 70 latter threaded for the engagement of a nut 13.

14 is a tubular collar having internal threads 15 which receive a threaded plug 16 having a ratchet face 17 which is adapted 75 to engage the face 11 in the manner of such devices.

18 is a coil spring for holding the ratchet faces in engagement.

19 is a hand-lever loosely seated in the 80 plug 16.

20 designates either one of a suitable number of rollers loosely and removably seated in the casing 2. Each has a hemispherical head portion 21 and preferably a similarly shaped foot portion 22. By reference to Fig. 1 it will be seen that the contact of the head 21 against the casing wall, especially the front portion thereof, and thereby the friction, is, because of the hemispherical form thereof, much reduced. Each roller is tapered, the degree thereof being greater than that of the mandrel, so that when the rollers are occupying the positions shown in Fig. 1 a circle described by their points of greatest diameter, would be greater than that in any lower plane with the device considered as standing in the position shown in Fig. 1. The smaller end of the roller is of such diameter that it may pass bodily 95 through its slot 4, but the larger end portion is of greater diameter than the width of said slot, whereby the roller itself is securely retained.

In operation, the fore end of the device is 105 inserted into the end of a flue 23 until the bosses 7 rest against the flue-sheet 24, whereupon the operator will force the mandrel forward until it is sufficiently tight, and will then operate it by means of the lever 110 19 which will impart rotary movement to the plug 16 to move the ratchet 11—17 in

such a manner as to turn the mandrel, the friction of which will rotate the rollers, each on its axis, and the rollers will cause the casing to turn. The mandrel being forced 5 forward the rollers will gradually expand that portion of the flue which lies just inward of the flue-sheet, until it assumes the conic contour shown at α . As the flue is expanded (in use, by the heat) it will elongate 10 and thus force itself more tightly into the flue-hole 25, and simultaneously its transverse expansion will "swell" it therein.

Having thus described my invention, I claim as new and desire to secure by Letters 15 Patent the following, namely:

1. Combined in a device of the character described, a tubular casing having slots in its wall, tapered rollers loosely arranged one in each slot, a tapered mandrel arranged in said casing and said rollers being reversible in said slots and the smaller portion of each less in diameter than the width of the slot

in which it lies and its taper greater than that of the mandrel, a ratcheted head on said mandrel, and ratcheted means for rotating said head. 25

2. Combined in a device of the character described, a tubular casing having slots in its wall, tapered rollers loosely arranged one in each slot, a tapered mandrel working in said casing and adapted to actuate said rollers, the smaller end of each roller being of less diameter than the width of the slot in which it lies and its taper greater than that of the mandrel, a ratcheted head on 30 said mandrel, and ratcheted means for rotating said head. 35

In witness that I claim the foregoing I hereunto affix my signature, in presence of two subscribing witnesses.

WILLIAM O. FROME.
